UNITED STATES PATENT OFFICE.

FRITZ HOFMANN, KONRAD DELBRÜCK, AND KURT MEISENBURG, OF ELBERFELD, GERMANY, ASSIGNORS TO FARBENFABRIKEN VORM. FRIEDR. BAYER & CO., OF ELBERFELD, GERMANY, A CORPORATION OF GERMANY.

PROCESS FOR PRODUCING BETA-GAMMA-DIMETHYLERYTHRENE.

1,076,575.

Specification of Letters Patent.

Patented Oct. 21, 1913.

No Drawing. Original application filed May 9, 1912, Serial No. 696,160. Divided and this application filed August 15, 1912. Serial No. 715,252.

To all whom it may concern:

Be it known that we, FRITZ HOFMANN, KONRAD DELBRÜCK, and KURT MEISENBURG, doctors of philosophy, chemists, citizens of the German Empire, residing at Elberfeld, Germany, have invented new and useful Improvements in Processes for Producing Beta-Gamma-Dimethylerythrene, of which the following is a specification.

10 The present application is a divisional application of the application Serial No. 696160, filed May 9, 1912 and concerns a new and valuable process which results in an excellent yield of the erythrene hydrocarbon beta-gamma-dimethylerythrene and which consists in heating pinacone with a small quantity of a sulfonic acid. The use of a small amount of acid (less than the amount of pinacone reacted upon) results in much 15 larger yields of the hydrocarbon than has been obtained by processes heretofore known. With a fraction of a per cent. only 20 of the acid unusually large yields are obtained.

25 The process proceeds according to the following equation:

In order to illustrate the new process more fully the following example is given, 30 the parts being by weight:—1000 parts of pinacone are heated with 1 part of naphthalene-1.5 disulfonic acid to 130°—140° C. Dimethylerythrene and water distil over besides pinacone hydrate and small quantities 35 of pinacolin. The beta-gamma-dimethylerythrene isolated from the mixture boils at 68°—69° C.

Instead of the above mentioned sulfonic acid other sulfonic acids, such as mono- or 40 naphthalene-trisulfonic acids, etc., can be used.

We claim:—

1. The process of producing an erythrene hydrocarbon which comprises distilling a pinacone with an amount of sulfonic acid 50 substantially less than the amount of pinacone reacted upon.

2. The process of producing an erythrene hydrocarbon which comprises distilling a pinacone with a fraction of a per cent. of 55 a sulfonic acid.

3. The process of producing an erythrene hydrocarbon which comprises distilling a pinacone with a fraction of a per cent. of 60 a naphthalene-sulfonic acid.

4. The process of producing an erythrene hydrocarbon which comprises distilling a pinacone with a fraction of a per cent. of 65 naphthalene-1.5-disulfonic acid.

5. The process of producing an erythrene hydrocarbon which comprises distilling a pinacone with about one tenth of one per 70 cent. of a sulfonic acid.

6. The process of producing an erythrene hydrocarbon which comprises distilling a 75 pinacone with about one tenth of one per cent. of naphthalene sulfonic acid.

7. The process of producing an erythrene hydrocarbon which comprises distilling a pinacone with about one tenth of one per 80 cent. of a naphthalene-1.5-disulfonic acid.

8. The process of producing beta-gamma-dimethylerythrene, which process comprises first distilling pinacone with a fraction of a per cent. of a sulfonic acid and then separating the beta-gamma-dimethylerythrene, substantially as described.

9. The process of producing beta-gamma-dimethylerythrene, which process comprises first distilling pinacone with a fraction of 85 a per cent. of naphthalene-1.5-disulfonic acid and then separating the beta-gamma-dimethylerythrene, substantially as described.

10. The process of producing beta-gamma-dimethylerythrene which process comprises distilling pinacone with about one 90 tenth of one per cent. of a sulfonic acid and

then separating the beta-gamma-dimethyl-
erythrene, substantially as described.

11. The process of producing beta-gam-
ma-dimethylerythrene which process com-
5 prises distilling pinacone with about one
tenth of one per cent. of a naphthalene-1,5-
disulfonic acid and then separating the beta-
gamma-dimethylerythrene, substantially as
described.

In testimony whereof we have hereunto 10
set our hands in the presence of two sub-
scribing witnesses.

FRITZ HOFMANN [L. S.]
KONRAD DELBRÜCK. [L. S.]
KURT MEISENBURG. [L. S.]
